UNITED STATES PATENT OFFICE.

EDWARD E. CLEMENT, OF WASHINGTON, DISTRICT OF COLUMBIA.

ELECTRICAL SOUND-PRODUCING SYSTEM AND APPARATUS.

1,197,910.

Specification of Letters Patent. Patented Sept. 12, 1916.

Application filed August 28, 1911. Serial No. 646,553.

To all whom it may concern:

Be it known that I, EDWARD E. CLEMENT, a citizen of the United States, residing at Washington, in the District of Columbia, 5 have invented certain new and useful Improvements in Electrical Sound-Producing Systems and Apparatus, of which the following is a specification, reference being had therein to the accompanying drawing.

10 My invention relates to resonating systems and apparatus, and especially to such as employ horns, pipes and similar means for producing more or less sustained vibrations in a column of air.

15 The object of the invention is to produce, first a self-contained operative unit apparatus, and second a system of such units which may be controlled by direct connection with electrical selective circuits operated in a suitable manner.

20 To attain my objects, I provide a pipe or horn with an initial vibrator and a controlling device for the vibrator, mounted directly on the horn or pipe so as to form a self-contained, self-actuating unit, which needs only electrical energization to throw into vibration the column of air in the pipe or horn, and continuously vibrate the same; and I then combine a set of these self-contained unit pipes or horns, and connect them through electrical circuits with their proper selective devices and a source of current in a manner which will be hereinafter described. The source of current may also 25 if desired be located in or carried upon one of the units, together with a circuit controller, so that the unit is not only self-contained and self-actuating, but portable. This application is a continuation in part of a prior 30 copending application, filed August 11th, 1905, Serial No. 273,799, upon which Letters Patent No. 1,002,036 were granted to me August 29th, 1911.

35 My invention is illustrated as to some of its embodiments in the accompanying drawings, wherein the same figures and letters of reference point out the same parts throughout.

40 In the drawings, Figures 1 and 2 show the applications of my invention to megaphones or horns. Figs. 3 and 4 show details of the vibrator in Fig. 2, on an enlarged scale. Fig. 5 shows the invention applied to an organ pipe. Fig. 6 is a modification of the

same, showing an automatic vibrator reed 55 for the working magnet. Figs. 7 and 8 are diagrams showing vibrators controlled by perforated note sheets.

Referring to the drawings, Figs. 1, 2, 3 and 4 show a form of reactive sound-producing device particularly useful as a signal. As a combination of horn and megaphone I have devised the form shown in Fig. 1. This comprises the horn H, fitted with a mouthpiece h³, and having its rear end fitted with a small longitudinal frame of metal w', carrying the reed w² and the working magnet W adapted to vibrate the same. Inside the angle of the frame is a small microphone M, which may well be a granular cell of considerable current carrying capacity. An extension of the horn is shown at h' containing a dry battery cell B', and bearing on one side a push button circuit closer h. The operation of this device is as 75 follows: When the button is pressed to close the circuit, current from the battery passes through the magnet W and causes it to pluck the reed, which reacts on the microphone, which causes repeated plucks and so on until the column of air in the horn H is in full vibration. The reed and horn must be approximately in tune with each other, or at least the period of the horn must be so related to that of the reed that when the reed 80 is vibrated it will throw into sympathetic vibration the column of air in the horn, which resonates as long as current is passing through the windings of the magnet W. 85

When the sound is started and the microphone is working at its maximum the sounds of the voice in articulate speech may be superimposed upon the coarser undulations of the note of the horn. This effect of superposition is produced through the combined 90 action of the reed and microphone, the mouthpiece opening near the reed by preference.

In Fig. 2 the separate microphone is omitted, the reed carrying a back contact 100 which performs the function of the microphone of Fig. 1 replacing the multiple contacts of the microphone with a single buzzer contact. In starting up the sound in this case, the buzzer action starts the vibration 105 of the horn, and after the horn note is established it may take control of the buzzer armature, which vibrates in unison with it.

As a commercial product this form of the invention can be made very cheaply as a device for making a noise, and as a signal. The details are shown in Figs. 3 and 4.

5 The magnet W has an armature support consisting of a punched copper or brass plate extended out at one end and secured to the armature spring by the rivet w^4 . The two cores of the magnets are riveted directly to 70

10 the side of the horn with or without an interposed iron piece, depending on the material and thickness of the horn; and the armature w^2 , which constitutes both reed and circuit controller, is riveted to the spring w^5 ,

15 whose end normally engages the platinum point of the screw w^6 in the yoke w^7 , which is carried on the insulated head of one spool. While I have not shown a mouthpiece with this form of horn, it can be used therewith.

20 Figs 5 and 6 show my invention applied to the sounding of organ pipes. Fig. 5 shows a pipe P with the usual embouchure p, which for the purpose of this invention may be any form of aperture, outside which 85

25 a reed w^2 is mounted on the bracket or frame w' , which carries also the magnet W, placed so as to act upon the reed. The microphone M is attached to the lower end of the pipe, and a circuit is provided includ- 90

30 ing key K and wires 1, 2, 3 and 5. The operation of this form is substantially the same as those I have been describing, the reed starting a flutter in the pipe, which being taken up and resonated in the pipe causes a 95

35 constant action and reaction in unison, which maintains the sound full and rich, and of a strength depending upon the battery supply.

Fig. 6 shows a pipe similar to that of 40 Fig. 5, fitted with the form of vibrator shown in Figs. 3 and 4. The magnet W is carried on its bracket w' , bolted to the lower end of the tube P, and the reed w^2 with its attached parts are the same as in the other 100

45 figures previously described. After the reed starts to vibrating and the air in the pipe has taken up the sound and resonated it, the reed falls into unison with the pipe even if it were not previously exactly so.

50 Instead of the simple key shown in Fig. 5, I may also employ perforated strips of paper somewhat similar to pneumatic controller strips. Such an arrangement is illustrated in each of the diagrams Figs. 7 and 8, 105

55 and I shall claim the same in combination with the other elements of the invention, as I consider it of value where it is desirable to get a continuous tone by electrical control.

60 By electrical control I mean the application of energy to the sounding bodies electrically, and the control of the same by circuit closers. In applying the paper strip principle I perforate a paper in lines corre- 110

65 sponding in their spacing to the distances

between the set of contact springs connected in place of the keys K to the magnets. The springs rest on a common return metal plate or drum and the paper strip is fed along under them. As each perforation comes under a spring the latter presses through into contact with the roller or plate beneath and so closes the circuit of its magnet. The regulation of the speed of the rolls, and the provision of extra perforations and extra 75

70 springs for stops and other ancillary mechanism are all included in the scheme. I prefer to run the mechanism for the rolls by means of a small electric motor, so that the 80

75 control and regulation of the entire mechanism may be uniform.

In the claims I shall make use of several broad terms such as initial vibrator to indicate the reed or armature of the electromagnets; resonator or like term to indicate the 85

80 resonant body of air or the horn or pipe; and circuit controlling and variable resistance device to indicate a microphone or a pair of contacts coöperating with and reciprocally controlled by the electromagnet of 90

95 the vibrator.

Many modifications might be resorted to without departing in any way from the spirit or scope of the invention and all such are included within the purview of the ap- 95

90 pended claims.

Having thus described my invention, what I claim and desire to secure by Letters Patent is:

1. In a system of the class described, a 100

plurality of tuned pipes or horns, individual electromagnetic vibrators each mounted upon one of said tuned pipes or horns and forming therewith a self-contained unit, and each selectively and exclusively controlling 105

its own pipe or horn, a branch electric circuit for each vibrator, a source of current in the common part of said branches, and selective circuit closing means for said branch circuits, additional to the vibrators. 110

2. In a system of the class described, the 115

combination of a plurality of self-contained sounding units, each comprising a tuned resonating pipe or horn, with an electromagnetic vibrator mounted directly thereon and carried thereby, a plurality of branch circuits each including one of said vibrators, a source of current common to said circuits, and means common to all the vibrators for controlling them selectively.

3. In a system of the class described, a 120

plurality of electrically energized, self-contained sound-producing units tuned to furnish different notes in a musical scale; each comprising an initial vibrator, electromagnetic means for actuating the same, circuit-controlling means for said electromagnetic means; and a resonator in acoustic communication with the initial vibrator and tuned so as to amplify the sound produced thereby, 125

130

said circuit-controlling means being responsive to the vibrations of said vibrator to render its action continuous; means for supplying current to the several units; all in combination with a plurality of branch circuits each including one of the several units, and means additional to the circuit-controlling means of the several units, for individ-

ually and selectively controlling the several circuits.

In testimony whereof I affix my signature in presence of two witnesses.

EDWARD E. CLEMENT.
